UNITED STATES PATENT OFFICE.

HERMANN HIRSCH, OF 4, 5, AND 6 GREAT SAINT HELENS, COUNTY OF MIDDLESEX, GREAT BRITAIN.

PADDLE-WHEEL.

SPECIFICATION forming part of Letters Patent No. 247,564, dated September 27, 1881.

Application filed May 24, 1881. (No model.) Patented in England June 19, 1880, in Belgium December 17, 1880, and in France December 18, 1880.

To all whom it may concern:

Be it known that I, HERMANN HIRSCH, a subject of the Emperor of Germany, residing at 4, 5, and 6 Great Saint Helens, in the county 5 of Middlesex, Kingdom of Great Britain and Ireland, have invented new and useful Improvements in Paddle-Wheels, (for which I have obtained a patent in Great Britain, No. 2,498, bearing date June 19, 1880,) of which the following is a specification.

This is a division of an application for patent filed February 11, 1881, serial No. 25,897, which embraced the same subject-matter.

My invention relates to improvements in the 15 shaping and constructing of paddle-wheels; and it consists in giving to such structures alternately-curved lines or undulated formations, such as hereinafter described, and which are 20 designed to afford harmony of contact between the water and the structure therein immersed, to allow the water to be displaced with ease and to diminish friction.

Figure 28 is a group of seven circles. A 25 thick black line is produced by portions of the circumferences of any two adjacent circles—as, for instance, S' T' of the outer six, and of the central one, U'. Such line constitutes the germinial curve, which I employ in designing the 30 floats of a paddle-wheel according to my invention.

Figs. 29 and 30 show face and edge views, respectively, of a single float, which may be constructed of any suitable material—as, for instance, iron or steel—Figs. 31 and 32 showing face and edge views of the same float prior 35 to its having had imparted to it the edge flexure shown by Fig. 30. The float is so mounted upon the frame, structure, or arms of the wheel as to allow of the point V' being the most distant spot of the float's surface from the axis of 40 the engine-shaft. In going ahead the float is made to impinge upon the water in the direction shown by the arrow on Fig. 30.

Fig. 33 is a portion of a side view of a complete paddle-wheel furnished with floats according to my invention, Fig. 34 being a view,

at right angles to Fig. 33, of a like fragmentary portion of such complete paddle-wheel.

It will be evident that, although the paddle-wheel I have shown by way of illustration is 50 of the "radial" or "fixed-float" type, my invention is nevertheless equally applicable to paddle-wheels having feathering floats.

It will be observed that my paddle is curved on both sides and along both edges. This formation gives easy contact between the water and the paddle. Were the curvature but one way the effect would be lost, as in plunging into and passing through the water the beat of the waves is felt at every point.

Having described the nature of my said invention and explained in what manner the same is to be or may be performed or carried into practical effect, I would have it understood that although I have described and shown the undulated surfaces and edges as being composed of arcs of circles in compliance with the normal diagram shown, yet other curves of approximate contour (including, for example, portions of ellipses) may in some cases be adopted for 70 any or all of the constituent elements of such undulated surfaces, (see, for examples, Figs. 34A, 34B, 34C, and 34D,) according to my invention, the object being, as I have already stated, to afford harmony of contact with the water; also, I would remark that the number 75 of undulations may be varied to suit the circumstances of particular applications without departure from the essential characteristics of my invention, as respects which

What I claim as novel and original is as follows:

The paddle-wheel float described, having alternately curved or undulated faces and alternately curved or undulated edges, substantially as hereinbefore described, and shown in the accompanying drawings.

HERMANN HIRSCH.

Witnesses:

GEORGE WALLERS,
PHILIP WALKER.
